US00D378694S

United States Patent [19]Colling et al.*Patent Number: Des. 378,694*Date of Patent: Apr. 1, 1997*[54] FISHING ROD FLOAT

[76] Inventors: Thomas P. Colling, 58319 Kimber, Washington, Mich. 48094; Jo-Ed Spitzer, 2997 Walton Blvd., Auburn Hills, Mich. 48326

[] Term: 14 Years

[21] Appl. No.: 38,196

[22] Filed: May 1, 1995

[52] U.S. Cl. D22/139; D22/134

[58] Field of Search D22/134, 139, D22/146; D3/260, 23, 25, 20, 25.2, 54.1, 57.1; 206/315.11; 441/8

[56] References CitedU.S. PATENT DOCUMENTS

D. 252,336 7/1979 Grippi, Jr. D3/260

D. 327,726	7/1992	Lowrance et al.	.....	D22/139
D. 363,529	10/1995	Nordstrom	.....	D22/139
3,786,590	1/1974	Weeks	.....	43/25
4,583,314	4/1986	Kirkland	.....	43/25
4,766,690	8/1988	Troha	.....	43/25
5,203,104	4/1993	Brauer	.....	43/23

Primary Examiner—Doris V. Coles

[57] CLAIM

The ornamental design for a fishing rod float, as shown and described.

DESCRIPTION

FIG. 1, is a perspective view of a fishing rod float; FIG. 2, is an end view, the opposite end view being identical; and, FIG. 3, is a top view of the fishing rod float, showing the slot which is cut into it, the bottom being plain and unadorned.

1 Claim, 1 Drawing Sheet

FIG. 1

FIG. 2

FIG. 3